UNITED STATES PATENT OFFICE.

JAMES FRED THOMAS, OF CLARINDA, IOWA.

BUST DEVELOPER.

Application filed October 10, 1921. Serial No. 506,803.

To all whom it may concern:

Be it known that I, JAMES FRED THOMAS, a citizen of the United States, residing at Clarinda, in the county of Page and State of Iowa, have invented certain new and useful Improvements in Bust Developers; and I do declare the following to be a full, clear, and exact description of the invention, such as will enable others skilled in the art to 10 which it appertains to make and use the same.

My invention relates to bust developers of the form in which the breast is expanded into a suction cup with the nipple received 15 in a supplemental cup within the aforesaid cup, provision being made for exhausting the air from both cups thru a tube leading from the nipple-receiving cup.

One object of the invention is to connect 20 a suction bulb directly with the tube which extends outwardly from the nipple-receiving cup and to extend a flexible sleeve from the bulb to the neck of the outer cup through which the tube passes, whereby to establish 25 an effective air tight connection.

A further aim is to mount the above mentioned tube slidably in the neck of the outer cup so that the bulb may serve as a handle for moving it inwardly and outwardly to 30 produce an added massage action on the nipple of the breast after that nipple is received in the relatively small inner cup.

With the foregoing in view, the invention resides in the novel subject matter herein- 35 after described and claimed, the descriptive matter being supplemented by the accompanying drawings.

Figs. 1 and 2 are sectional views showing the relation of parts prior to reception of 40 the nipple in the inner cup and after reception of said nipple in the cup and outward movement of the latter.

In the drawings above briefly described, the numeral 1 designates a suction cup 45 formed of glass, celluloid, hard rubber, or any other desired material and of a size to accommodate a human breast when the latter is expanded by suction into the cup. The closed end of the cup 1 is provided with an 50 outward bulge or bell 2 from which a neck 3 extends, the outer end of said neck being provided with an external rib 4. Passing slidably through the neck 3 is a non-yielding tube 5 whose inner end is formed with a 55 small suction cup 6 adapted to receive the nipple of the breast when the latter has been

expanded in the cup 1 to a pre-determined extent. The outer end of the tube 5 is connected in any suitable way with a suction bulb 7 which is commonly formed of rubber, 60 the end or neck 8 of the bulb being provided with a rib 9 snapped into a groove 10 in the outer end of the tube 5 so as to establish an effective connection between the two, by means of which it is insured that inward or 65 outward movement of the bulb 7, shall similarly move the tube 5 and the nipple-receiving cup 6.

To establish an air tight connection between the tube 5 and the neck 3, I provide 70 the neck 9 of the bulb 7 with an integral sleeve or skirt 11 whose lower end 12 is snapped around the neck 3 under the rib 4. The dimensions of the skirt 11 are such that it will readily permit inward and out- 75 ward sliding of the tube 5 as will be clear by comparing Figs. 1 and 2.

As common with devices of this character, the bulb 7 is equipped with an air expelling valve 13 through which escape of air takes 80 place when the bulb is compressed. When this action takes place, a small check valve 14 in the tube 5 closes so that no air can be driven into either of the suction cups. When now the pressure on the bulb is released and it 85 becomes distended under its inherent resiliency, the valve 14 opens, the valve 13 closes, and suction is consequently produced through the tube 5. This suction, when the cup 1 is placed over the breast as seen in 90 Fig. 1, will expand the latter as shown by the dotted lines so that eventually the nipple is received in the small cup 6. A massaging action may now be produced upon the nipple by continually operating the bulb 7 and in 95 addition, the entire breast may be stretched outwardly by pulling upon the bulb to slide the tube 5 and cup 6 outwardly into the bell 2 as illustrated in Fig. 2. By constructing the device in, or approximately in the manner shown and described, great stimulation and development of the breast may be effected in a simple and convenient manner and since excellent results may be obtained from the details disclosed, they may well be 100 followed. I wish it understood, however, that within the scope of the invention as claimed, numerous minor changes may be made.

I claim:

1. A breast developer comprising a cup to receive the breast, said cup having an out-

wardly extending neck, a tube passing through said neck and having a nipple-receiving cup within the other cup, a suction bulb having its end secured upon said tube, and a flexible air tight sleeve extending from said end of the bulb around the outer portion of said tube and secured around said neck, said sleeve having air tight engagement with both said bulb and said neck.

10 2. A breast developer comprising a cup to receive the breast, said cup having an out-

wardly extending neck, a tube passing slidably through said neck and having a nipple-receiving cup within the other cup, a suction bulb having its end secured upon 15 said tube and serving as a handle to move said tube and its cup inwardly and outwardly.

In testimony whereof I have hereunto set my hand.

JAMES FRED THOMAS.
